VELOCITY MODULATED TUBE OF THE REFLEX TYPE

Jean Bernier and Jean Brossart, Paris, France,
assignors to Compagnie Generale de Tele-
graphie Sans Fil, a corporation of France

Application April 27, 1949, Serial No. 90,002

Claims priority, application France May 5, 1948

3 Claims.

(Cl. 315—5)

1

Our invention relates to velocity modulated tubes of the so-called reflex type, in which a so-called reflecting electrode, which is negatively biased with respect to the accelerating electrodes, reflects the velocity modulated electrons that have come out of the high-frequency field, so as to cause them to travel across said field in the opposite direction and suitably in phase to effect an absorption of energy from the beam. These tubes only use one resonant cavity, which simplifies construction and provides facilities for tuning and adjusting the circuits of the tube.

In such tubes, there exists in the space between the reflector and the electrode bounding the high-frequency field, a very substantial space charge that corresponds to substantially twice the cathode current. Owing to this space charge, the trajectories of the electrons are not straight, whereby the satisfactory operation of the tube and in particular its efficiency, is impaired. It can in fact be seen, by considering Fig. 1 which shows schematically a reflex tube of the usual type comprising a beam 1, a resonant cavity 2 and a reflector 3, that the electrons are not properly focussed on the return travel and numerous electrons shown as stream *a* are caught by the solid elements of the reflecting space instead of returning between the high-frequency grids, and that electrons belonging to different current streams *b* and *c* that flow in phase across the high-frequency field in the initial direction have unequal times of transit through the reflecting space, so that the various electron current elements are no longer in phase when they return into the high-frequency field.

This drawback particularly affects reflex klystrons, the cathode of which has a perveance, which term is used to designate the coefficient *k* of the cathode emission equation

$$I_0 = kV_0^2$$

of the order of 3, *I*₀ being expressed in microamperes and *V*₀ in volts, producing an emission of 15 milliamperes at 300 volts or 94 milliamperes at 1000 volts, that is to say low voltage or medium power tubes, or the so-called wide electron tuning band tubes operating at high voltage, since in tubes of this type the reflecting space is sufficiently large for the divergence effect of the beam shown in Fig. 1 to be noticeable.

Our invention is intended to eliminate this drawback by introducing in reflex tubes improvements such that, despite a considerable space

2

charge, the trajectories of the electrons remain substantially straight in the reflecting space and each electron follows substantially the same trajectory on the return travel as on the initial travel, so that the mean transit time of the electrons through the reflecting space remains very substantially the same in each of the trajectories. The invention can also be advantageously used in systems, such as certain microscopes, wherein the electron optical system comprises mirrors; in particular, it enables certain aberrations to be corrected.

The invention essentially comprises arranging an intermediate electrode between the anode and the reflector of the tube, in the region that corresponds to the formation of a virtual cathode for the return beam, and giving to the surfaces bounding said electrode, and also to the surfaces of the anode and of the reflector, such a shape that:

The outer surface of the intermediate electrode determines with the surface of the reflector a practically uniform distribution of the field between said electrode and the reflector, and that:

The inner surface of the intermediate electrode determines with the surface of the anode a distribution of field between said electrode and the anode such that the electrons are kept along straight trajectories.

The shapes of the surfaces in question are calculated in a variable manner according to the voltages applied to the intermediate electrode, according to the shape of the beam, and the like.

The invention will be more clearly understood, by considering the accompanying Figures 1 to 4, in which:

Figure 1 is a schematic view of a conventional klystron.

Figure 2 shows a diagrammatic section in an axial plane, of a klystron provided with the improvements according to the invention.

Figure 3 shows a modification of the klystron of Figure 2, in which the electron beam is hollow.

Figure 4 shows, like Figure 3 another modification of the klystron of Figure 2 which allows some improvements in the operation of said klystron.

Fig. 2 shows a diagrammatic section of a system of electrodes of a reflex tube according to the invention. This section may be considered for example as an axial section of a system with a cylindro-conical beam of the shape of a body of revolution about the axis *Oy*, but it is to be understood that it could also be considered as showing a meridian section of a system with a

beam of the shape of a disc of revolution about the axis $0x$, or a cross-section of a system with a flat beam and a prismatic cavity.

Fig. 2 shows a beam of electrons 6, for example a conical beam, which successively passes across the resonant cavity 2 and the anode 8 which is raised to the acceleration potential of the electrons, said beam being reflected by means of an electrode 3 raised to a negative potential with respect to the cathode 7. The points of the space at which the electrons return backwards form an equipotential surface at zero potential which is located between the electrodes 3 and 8 and which may be considered as a virtual cathode. The space charge in the beam is thus that produced by a current twice the strength of the cathode current, it is the same as the space charge which would exist in a beam of the same shape, emitted by a cathode which is of the shape of the equipotential surface located in the position of the virtual cathode, but which produces, contrary to a real cathode, an electric field which is not zero at the level thereof.

According to the invention, between the electrodes 3 and 8 is arranged an intermediate electrode 9, the location of which coincides with the region of formation of the virtual cathode.

The system should be dimensioned as regards distances and potentials applied, in such a manner that the point of formation of the virtual cathode corresponds to the desired time of transit, and the electric field in the region in which there is no space charge between the virtual cathode and the reflector is precisely equal to the field subsisting at the level of the virtual cathode.

For the trajectories of the electrons to be straight and for the return trajectories to coincide exactly with the initial trajectories, it is necessary that the equipotential surfaces within the beam, taking into account the space charge, be portions of concentric spheres and that the trajectories of the electrons be the radii of said spheres.

Preferably, therefore, the surface of the reflector 3 may be given the shape of a spherical segment which is concentric with the orthogonal spheres of the trajectories of the electrons, and the outer surface of the electrode 9 may be given a shape parallel to the electrode 3, so that the electric field in the region in which there is no space charge and which is located between 3 and 9 will be definitely uniform, since the equipotential surfaces are spherical segments. The electrode 9 is provided with a circular hole of a diameter substantially equal to that of the beam at the level of its reflecting surface; this hole may be covered, although this is not essential, with an open-mesh grid 4 of the shape of a spherical segment which is concentric to 3. Said grid has no electron-optical lens effect, since the shape of the electrodes and the voltages have been chosen, as hereinbefore stated, in such a manner that the electric field on either side of the grid 4 is the same; the purpose of this grid is merely to constrain the equipotential surface to be of spherical shape and thereby prevent said surface from being deformed by an overlap of the field through the hole in 9, which might produce a fault in the optical properties of the mirror. Nevertheless, as already stated, the grid 4 is not essential.

The anode 8 is also provided with a hole for the electrons to pass through; this hole is preferably covered, although this is not essential, with an open-mesh grid 5 of the shape of a spherical segment which is concentric to 8.

with a spherical grid 5 which is at right angles to the trajectories of the electrons and which may serve to bound the high-frequency field of the cavity 2. It should be noted that since the electric fields on either side of the grid 5 are not equal, said grid forms a lens which must be taken into account for determining, by the well known means, the angle of divergence of the cone knowing the angle of incidence of the electrons before they pass through the grid 5.

13 is the vacuum tight envelope of the tube. In said vacuum chamber is shown a cathode 7 heated by a filament 14, and a focusing electrode 15. The reflector 3 is raised to a negative potential through the connection 18 and the intermediate electrode is raised through the connection 19 to a suitable potential.

20 The shape of the inner face of the electrode 9 and also the shape of the anode 8 are determined by the condition that the distribution of the potential between 8 and 9 should be such that the forward and return trajectories of the electrons coincide and are straight.

25 Starting from this condition, it is possible to determine said shape for any shape of the beam, partly by calculation and partly by experiment.

30 The method of calculation may be based on the following procedure: the potential of the anode 8, the cathode current flowing through the beam during the forward travel, the diameter and the angle of incidence of the beam at the level of the grid 5, and the distance between the grids 4 and 5 which is determined by the desired time of transit, are given. The density of 35 the electron charge ρ in the portion 6 of the beam is calculated and the electron-optical equations relating to the passage through the grid 5 are written down, and also Poisson's equation:

$$40 \quad \Delta v = \frac{\rho}{\epsilon_0}$$

wherein ϵ_0 denotes the dielectric constant of the vacuum in rationalized Giorgi units.

45 The graphic or analytic solution of these equations makes it possible to determine the angle of divergence 28, of the beam, the law of distribution of the potential inside the beam between the electrodes 8 and 9, and the electric field at the level of the virtual cathode located at 4.

50 It is then possible to determine the radii of the spherical surfaces 4 and 5, the diameter of the hole in the electrode 9, and the radius and the voltage of the spherical electrode 3 which have to be such that the field at the level of the 55 grid 4 in the space 3-9 without any charge is equal to the field hereinbefore determined at the level of the virtual cathode.

55 For determining the shape of the anode 8 and of the inner surface of the electrode 9, it is possible to use, as is known, experiments in an electrolytic tank carried out on an enlarged model; the beam is represented by an insulating substance, and by deforming the electrodes representing the opposite surfaces of the electrodes 60 8 and 9, attempts are made to produce in the electrolyte a potential distribution which coincides, along the insulating surface representing the beam, with the distribution of the potential obtained by integrating Poisson's equation.

65 Fig. 3 shows a modification of a detail of Fig. 2, in which the beam 6 is hollow. The elements of Fig. 2 are repeated therein, viz. the reflector 3, the anode 8 and the intermediate electrode 9. The grid 4 of said electrode 9 has at the middle 75 thereof a solid conical portion 11 which, for the elimination of a slight leak, has a

hollow region of the beam, performs the same focalizing function as the inner surface of the electrode 9 does for the outer regions of the beam.

Similarly, the anode 8 has at the middle thereof a recess 12, the shape of which is determined by means of the method hereinbefore explained.

Fig. 4 shows a modification of a detail of Figure 2 wherein the grids 4 and 5 of Fig. 2 are eliminated and the anode 8 is provided with thin noses 22 which, in addition to the non-negligible electron-optical effect that they have, tend to decrease the overlap of the high-frequency field which is favored by the elimination of the grids 4 and 5 and prevent said field from disturbing the grouping of the electrons in the reflecting space.

The reflector 3, the electrode 9 and the anode 8 are shaped according to the rules set forth which also define the characteristics of the system as regards dimensions and potentials, in such a manner that the beam 6 is reflected at the level of the grid 4 and follows on its return travel the same straight trajectories as during its forward travel.

At 20 is shown the lead of the circuit into which the high-frequency energy is delivered by the klystron.

The invention is not restricted to the embodiments described or to the applications considered but on the contrary admits of any modification in said embodiments and applications which might be within reach of an expert.

What we claim is:

1. A velocity modulation electronic tube comprising a source of electrons to be emitted in a beam, a velocity modulation cavity resonator having inlet and outlet grids interposed across the path of the beam, means comprising a connection between a first source of voltage and said resonator to raise the latter to a positive potential relatively to the said source of electrons, the surface of the resonator in the neighborhood of the outlet grid being concave in the direction of the beam, a reflecting electrode located in the axis

of the beam beyond the resonator a surface which is generated by a circle centered upon a point located inside the beam at a level where the cross-section of the beam is smallest, means comprising a connection between a second source of voltage and said reflecting electrode to polarize the latter negatively with respect to said source of electrons thereby to reflect the beam toward the resonator, an intermediate electrode placed between the resonator and reflecting electrode and having an aperture surrounding the axis of the beam, said aperture being located within the equipotential surface corresponding to the cathode voltage, said intermediate electrode being bounded on the one side by a surface generated by a circle concentric with the said circle generating the surface of the reflecting electrode, said surface of said intermediate electrode being homothetic to said surface of said reflecting electrode, and means comprising a connection between a third source of voltage and said intermediate electrode for raising the latter to a voltage approximately equal to that of said source of electrons.

2. A tube as claimed in claim 1, wherein the surface of said reflecting electrode and the surface of said intermediate electrode are spherical, and centered upon a point located inside the beam at a level where the cross-section of the beam is smallest, the aperture of said intermediate electrode being circular.
